SEWING MACHINE

Franklin A. Reece, Brookline, Mass.

Application March 26, 1940, Serial No. 325,983

35 Claims. (Cl. 112—112)

This invention relates to sewing machines of the type adapted to perform a predetermined number of stitching operations and automatically stop, and has for an object to provide an improved stop control for machines of this type whereby the number of stitching operations which will be automatically performed between the starting and the stopping of the machine is susceptible of wide variation at the will of the operator and in accordance with the requirements. The invention relates especially, although not exclusively, to machines for sewing on flat perforated buttons, and, when employed in machines of this type, provides means whereby the number and character of stitches automatically formed through one or two pairs of holes in a button can be widely varied and readily determined.

The invention will best be understood from the following description of a preferred embodiment thereof illustrated in the accompanying drawings, this, however, having been chosen for purposes of exemplification merely, as it will be obvious that the invention, as defined by the claims hereunto appended, can be otherwise embodied and used without departure from the spirit and scope thereof.

In said drawings:

Fig. 1 is a view, partly in side elevation and partly in longitudinal vertical section, of a button sewing machine having the invention incorporated therein.

Fig. 1a is a development of the cam for causing the needle to pass successively through two holes in the button.

Fig. 2 is a front elevation partly broken away.

Fig. 3 is a horizontal section taken substantially on the line 3—3, Fig. 1.

Fig. 4 is a fragmentary detail of the stop mechanism control.

Fig. 5 is a vertical section taken substantially on the line 5—5, Fig. 1.

Fig. 6 is a horizontal section taken substantially on the line 6—6, Fig. 5.

Fig. 7 is a vertical section taken substantially on the line 7—7, Fig. 1.

Figs. 8 to 12 are plan views illustrating different adjustments of the stop mechanism controller.

The invention is herein shown as incorporated in a button sewing machine the frame of which comprises a hollow base 20 (Fig. 1) and a hollow stitching head including an upright portion 21 and an overhanging arm 22. Journalled in bearings in the arm 22 is a main or stitching shaft

23 adapted to be driven from any convenient source of power through a belt pulley 24 under the control of stop mechanism hereinafter described. Mounted for vertical reciprocation in the forward end of the arm 22 is a needle bar 25 carrying a needle 26, said needle bar being reciprocated by the shaft 23 through suitable connections, generally indicated at 27, and herein shown as of the type described in the Reece Patent No. 2,193,344, March 12, 1940. Cooperating with the needle 26 is a rotary looper or hook 28 carried by a looper shaft 29 journalled in bearings in the base 20 and driven from the main shaft 23 by suitable power transmitting means, herein shown as a link belt or sprocket chain 30. The rotary hook or looper may be of any usual form but as shown is of the ring type described in the Kohler and Lachman Patent No. 393,766, December 4, 1888, and supported and driven by devices such as those shown in the Bolton Patent No. 376,364, January 10, 1888. The work plate 31 for supporting the work W for the attachment of a button B forms part of a frame 32 in an overhanging arm of which is guided a spring pressed presser foot bar 33 carrying at its lower end a button clamp generally indicated at 34. Specifically the parts above referred to form no portion of the present invention and may be of any suitable construction and arrangement.

As herein shown, the frame 32 is provided with a lug 35 secured to a rock shaft 36 mounted to oscillate and move axially in bearings 37 depending from the arm 22. Oscillation of said shaft produces a lateral vibration of the frame 32 to cause the needle 26 to pass successively through different holes of a pair in the button B, while axial movement of said shaft causes a longitudinal movement of the frame 32 to position the button for the operation of the needle through different pairs of holes.

Oscillation of shaft 36, and consequent lateral vibration of the frame 32, is produced by a bell crank lever 38 (Fig. 2) fulcrumed on the shaft 36 and having a depending fork or yoke 39 embracing a portion 32a of the frame 32. The arm 40 of the bell crank 38 is connected by a link 41 with a lever 42 pivoted at 43 in the arm 22 and having a cam follower 44 alternatively engageable through openings 45 in said lever with cam grooves 46 and 47 in the side of a cam 48. The link 41 is connected with the arm 40 by a pivot 49 longitudinally adjustable in an arcuate slot 50 in the arm 40 whereby the amplitude of vibration of the frame 32 produced by the cam

grooves 46 and 47 may be varied in accordance with the spacing of the holes in the button.

The cam 48 is formed with a worm gear 55 (Figs. 3 and 5) meshing with a worm 56 on the shaft 23, the gear ratio in the present instance being 24 to 1, so that the cam makes one complete rotation for each 24 reciprocations or thrusts of the needle, conveniently referred to as "stitches." As shown most clearly in Fig. 1a, each of the cam grooves 46 and 47 comprises sinuous portions 67 of such form as to cause the work and button holder to be moved alternately in opposite directions at each reciprocation, or between successive thrusts, of the needle, said sinuous portions being interrupted by straight portions 58 to cause the needle to pass twice, or make two thrusts through the same hole in the button to form a tying stitch. In the construction shown, the cam groove 46 includes two straight portions 58 spaced 180° apart to cause a tying stitch to be formed during the last two of each twelve reciprocations or thrusts of the needle, thereby producing what may conveniently be called a twelve-stitch group including and completed by a tying stitch, while the cam groove 47 includes three straight portions spaced 120° apart to cause a tying stitch to be formed during the last two of each eight reciprocations of the needle, thereby producing an eight-stitch group likewise including and completed by a tying stitch.

The rock shaft 96 is moved longitudinally to position the work for sewing through the several pairs of holes of a four hole button by means of a lever 63 (Figs. 1 and 6) having at its end a stud 64 engaging a circumferentially elongated opening in a collar 65 secured to said shaft 96. The lever 63 carries intermediate its ends a cam follower 66 adapted to engage a groove 67 in a cam 68 rotated from the cam 48 as hereinafter more particularly described. The cam groove 67 comprises two radially offset portions of equal length so that the work will be shifted from one pair of holes to the other in one direction or the other at each 180° movement of the cam 68. The lever 63 is fulcrumed on a stud 69 adjustable longitudinally of the lever to vary the axial movement imparted to the rock shaft 96 in accordance with the spacing of the pairs of holes in the button. The cam follower 66 comprises a pin slidably mounted in the lever 63 and connected by a lever 70 with a second similar pin 71 adapted to engage an opening in a lug 72 projecting inwardly from the frame and provided externally of the latter with an operating handle 73. By operating the handle 72 the cam follower 66 can be withdrawn from the cam groove 67 and the lever 63 locked to the frame to prevent any longitudinal shifting of the work in sewing a two-hole button.

The stop mechanism for operatively connecting the pulley 24 with the shaft 23 and disconnecting the same therefrom specifically forms no part of the present invention and may be of any suitable well known type. As shown in Figs. 1 and 7, this mechanism comprises an annular flange 76 formed on the pulley, said flange having a notch 77 to receive a latch or dog 78 pivoted to a collar 79 on the shaft 23, said latch being normally urged in the direction to engage said notch by a spring-pressed plunger 80. Cooperating with the latch 78 is a stop arm 81 having a resiliently yielding head 82 and secured to a rock shaft 83 journaled in the frame. When the stop arm 81 is in the position shown in full

lines in Fig. 1, the latch 78 is free to engage the notch 77 and the shaft 23 is connected with the pulley 24 for rotation thereby. For convenience in moving the stop arm into this position to start the machine the rock shaft 83 is provided with an arm 84 connected by a link 85 with a suitable treadle, not shown. When the stop arm 81 is in the position shown in dotted lines in Fig. 1 the head 82 is located in the path of movement of the latch 78 as the shaft rotates in the direction of the arrow in Fig. 7. Engagement of the latch 78 with the head 82 causes said latch to be disengaged from the notch 77, thereby disconnecting the pulley 24 from the shaft 23 and positively stopping the latter, the stopping impact being cushioned by yielding of the head 82, and the recoil being checked to bring the shaft to rest in a predetermined angular position by the engagement of a spring controlled dog 86 carried by the head 82 with a lug 87 on the collar 79. The stop arm is yieldingly held in either of the above positions by a spring pressed positioning plunger 88 (Figs. 1 and 3) carried by the arm 84 and engageable with recesses 89 in the frame.

Referring to Fig. 5, the cam 68 is keyed or otherwise secured to an upright shaft 95, journaled at its lower end in a bearing 96 in the lower wall of the arm 22 and at its upper end in a sleeve 97 clamped in a split hub 98 carried by an arm 99 formed on a ring 100 secured to the top of the arm 22 about an opening in the latter which is normally closed by a removable cap 101. The shaft 95 is formed with a key-way 102 to receive a sliding key 103 movable into upper and lower positions in either of which it is removably held by a spring-pressed locking pin 104 adapted to engage apertures 105 therein. When in its upper position, shown in Fig. 5, the key 103 engages a key-way 106, formed in the interior of the cam 48, so that the shaft 95 and cam 68 carried thereby are rotated directly by and in unison with the cam 48. When the key 103 is in its lower position, it engages a key-way 107 in a gear 108 rotatably mounted on the shaft 95 in a recess 109 in the cam 48. The gear 108 is formed with internal teeth 110 meshing with a pinion 111 journaled in the cam 48 and connected for rotation in unison with a coaxial pinion 112 likewise journaled in said cam and meshing with a fixed pinion 113, secured to or formed integral with the sleeve 97. The gear 108 and pinions 111, 112 and 113 constitute 3 to 2 gearing connecting the cams 48 and 68, so that when the parts are so connected, the shaft 95 and cam 68 will make one complete rotation for each movement of 240° of the cam 48.

Referring to Figs. 3, 5, 8, 9 and 10, mounted in a recess in the top of the cam 48 for angular adjustment about the axis of said cam and the shaft 95, is a disk 120, said disk, in combination with the cam 48, constituting a rotary controller for the stop mechanism above described. The cam 48 is formed about its upper edge with a circumferential series of spaced notches 121, while the disk 120 is formed about its edge with a series of similar notches 122. The notches 121 and 122 are differently spaced, and, by angularly adjusting the disk 120 with respect to the cam 48, said notches of the two series can be brought into register in different combinations. The disk 120 is retained in angularly adjusted position with respect to the cam 48 by a pin 123 adapted to engage a socket 124 (Fig. 5) in the cam 48 by inserting the same through any one of an arcuate series of openings A, B, C, and D in the

disk 120. With the pin 123 inserted through the opening A, as shown in Fig. 3, four pairs of notches 121, 122 are brought into register at points spaced 90° about the periphery of the controller, as indicated at a. With said pin inserted through the opening B, as shown in Fig. 8, two pairs of notches are brought into register at diametrically opposite points, as indicated at b. With said pin inserted through the opening C, as shown in Fig. 9, only one pair of notches are brought into register, as indicated at c. With said pin inserted through the opening D, as shown in Fig. 10, three pairs of notches are brought into register at points spaced 120°, as indicated at d.

Cooperating with the controller is a dog 125 having a nose 126 adapted to engage the periphery of said controller and to enter the notches 121, 122, said nose being of such width as to enter said notches only when a pair of notches is in register. As shown most clearly in Fig. 3, the dog 125 is pivoted at 136 to an arm 127 pivoted at one end at 128, to the frame, said pivotal connection 136 being intermediate the ends of the arm 127, and said dog being normally urged toward the controller by a spring 129. The arm 127 is connected at its free end, by a link 130 (see also Fig. 1), with the upper end of a lever 131 pivoted intermediate its ends, at 132, to the frame. The lower end of the lever 131 is connected by a link 133 with the stop arm 81. The dog 125 is formed with an inclined end 134 adapted, when said dog is moved toward the left, as shown in Fig. 3, to engage a fixed pin 135, thereby causing the nose 126 to be withdrawn from the controller notches, as illustrated in Fig. 4.

In operation, when the nose 126 of the dog 125 enters a pair of registering notches in the controller, continued rotation of the latter causes said dog to be drawn toward the left in Fig. 3, carrying with it the arm 127 which, through the link 130, lever 131 and link 133, causes the stop arm 81 to be moved into the position shown in dotted lines in Fig. 1 to stop the machine. When said stop arm is so moved, and just prior to the stopping of the machine, engagement of the end 134 of the dog with the pin 135 causes the nose 126 to be withdrawn from the registering notches in order to permit the subsequent movement of the arm 81 into the full-line position by the treadle connections to re-start the machine.

In addition to the openings A, B, C, and D, the disk 120 is formed with a short radial slot 141 which, when said disk is adjusted into the angular position shown in Figs. 11 and 12, registers with an eccentric socket 142 (Figs. 5, 11 and 12) in the top of the pinion 112, so that, as said pinion rotates, the disk 120 will be angularly oscillated to carry the notches 121, 122 at the 120° points alternately into and out of register, as illustrated at d in Fig. 11 and at d' in Fig. 12, respectively. The arrangement is such that each pair of notches at the 120° points is moved into and out of operation at alternate rotations of the controller. Consequently, a given pair d, d' of such notches will be inoperative to cause stoppage of the machine at one rotation of the controller but will be rendered operative at the next subsequent rotation of the controller. In other words, the parts being adjusted as shown in Figs. 11 and 12, the controller will act to stop the machine at each angular movement of 240°, the intermediate 120° stops being skipped.

With the cam follower 44, Fig. 2, engaged with 75

the cam groove 46, Fig. 1a, of the cam 48, and the pin 123 inserted in the socket 124 through the opening A, as shown in Fig. 3, the machine is stopped at each 90° movement of the cam 48 to form a six-stitch group and sews a tying stitch at the end of each second group. With the cam follower 44 similarly engaged, and the pin inserted through the opening B, as shown in Fig. 8, the machine stops at every 180° movement of the cam and sews a twelve-stitch group with a tying stitch at the end. With the cam follower 44 still similarly engaged, and the pin inserted through the hole C, the machine stops at the end of a complete rotation of the cam and sews two twelve-stitch groups, each completed by a tying stitch, and if the pin 71, Figs. 2 and 6, is withdrawn to unlock the lever 63, and the cam follower 66 engaged with the cam groove 67, these two groups will be sewn through the two pairs of holes in a four-hole button. With the pin 123 inserted through the opening D, as shown in Fig. 10, and the cam follower 44 engaged with the cam groove 47, the machine will stop at every 120° movement of the cam 48 and sew an eight-stitch group with a tying stitch at the end. With the cam follower 44 still engaged with the cam groove 47, and the pin 123 inserted in the socket 142 through the slot 141, the machine will stop at every 240° movement of the cam 48 and sew two eight-stitch groups with a tying stitch at the end of each group, and if the cam follower 66 is engaged with the cam groove 67 in the cam 68 and the key 103 shifted into its lower position in which the same directly connects the gear 108 with the upright shaft 95, these two groups will be placed in the two pairs of holes of a four-hole button.

It will thus be seen that the machine shown and described can be set to sew, automatically, groups of 8, 12, 16 or 24 stitches, each group being completed by a tying stitch irrespective of the number of stitches therein, and to stop at the completion of any of these groups, this being accomplished by the use (in conjunction with the stop mechanism described) of a single main cam 48 having two alternatively operative cam grooves and driven in constant time relation with the stitching mechanism. The machine can also be set to sew two 8 or 12 stitch groups and stop at the completion of the second group and, by the use of one additional cam 68 having a single cam groove, to place these two groups in the two pairs of holes of a four hole button.

The work holding mechanism of the machine above described is not claimed herein, being covered by the claims of a divisional application filed January 9, 1943, Serial No. 471,861.

I claim:

1. In a sewing machine having stitch-forming mechanism and stop mechanism therefor comprising a controller, means for moving said controller at a predetermined speed relative to the speed of operation of said stitch-forming mechanism, said controller including a plurality of parts adjustable into different relative positions, and a member controlled at all times jointly by said parts and operable, in accordance with the relative positions of said parts, to cause operation of said stop mechanism after the formation of a variable number of stitches.

2. In a sewing machine having stitch-forming mechanism and stop mechanism therefor, mechanism for controlling said stop mechanism comprising a controller, means for moving said controller at a predetermined speed relative to the

speed of operation of said stitch-forming mechanism, said controller including a plurality of relatively adjustable parts having differently spaced series of stop elements adapted upon the relative adjustment of said parts to be positioned in different combinations, and a member controlled at all times jointly by said parts, and operable, in accordance with the relative positions of said stop elements, to cause operation of said stop mechanism after the formation of a variable number of stitches.

3. In a sewing machine having stitch-forming mechanism and stop mechanism therefor, mechanism for controlling said stop mechanism comprising a controller having a plurality of parts formed with differently spaced series of stop elements, said parts being relatively adjustable into dispositions in which different stop elements of said parts complement each other, means for moving said parts together in timed relation with said stitch-forming mechanism, and a member operable upon engagement with only complemented elements to cause operation of said stop mechanism.

4. In a sewing machine having stitch-forming mechanism and stop mechanism therefor, mechanism for controlling said stop mechanism comprising a controller including a plurality of parts having differently spaced series of stop elements, said parts being relatively adjustable to position the stop elements of the respective parts in different combinations, means for moving said controller in timed relation with said stitch-forming mechanism, and a member operable upon engagement with stop elements of the respective parts which are relatively positioned in a certain predetermined way to cause operation of said stop mechanism.

5. In a sewing machine having stitch-forming mechanism and stop mechanism therefor, mechanism for controlling said stop mechanism comprising a controller having a plurality of parts formed with differently spaced series of stop elements, said parts being relatively adjustable to bring stop elements of the respective parts into register at variable points, means for moving said parts in timed relation with said stitch-forming mechanism and a member operable upon engagement with registering stop elements of the respective parts to cause operation of said stop mechanism.

6. In a sewing machine having stitch-forming mechanism including a stitching shaft and a stop mechanism for stopping said machine after the formation of a predetermined number of stitches, mechanism for controlling said stop mechanism comprising a rotary controller, means for rotating said controller at a predetermined speed relative to that of the stitching shaft, said controller including a plurality of coaxial disks having differently spaced series of stop elements and angularly adjustable to position the stop elements of the respective disks in different combinations, and a member operable upon engagement with stop elements of the respective disks which are relatively positioned in a certain predetermined way to cause operation of said stop mechanism.

7. In a sewing machine having stitch-forming mechanism including a stitching shaft and a stop mechanism for stopping said machine after the formation of a predetermined number of stitches, mechanism for controlling said stop mechanism comprising a rotary controller, means for rotating said controller at a predetermined

speed relative to that of said stitching shaft, said controller including a plurality of coaxial disks having differently spaced notches in their edges and angularly adjustable to position the notches of the respective disks in different combinations, and a member operable upon engagement with notches of the respective disks which are relatively positioned in a certain predetermined way to cause operation of said stop mechanism.

8. In a sewing machine having stitch-forming mechanism including a stitching shaft and a stop mechanism for stopping said machine after the formation of a predetermined number of stitches, mechanism for controlling said stop mechanism comprising a rotary controller, means for rotating said controller at a predetermined speed relative to that of said stitching shaft, said controller including a plurality of coaxial disks having differently spaced notches in their edges and angularly adjustable to bring notches of the respective disks into register at variable angularly spaced points, and a member operable upon engagement with registering notches of the respective disks to cause operation of said stop mechanism.

9. In a sewing machine having stitch-forming mechanism and stop mechanism therefor, mechanism for controlling said stop mechanism comprising a controller, means for moving said controller at a predetermined speed relative to the speed of operation of said stitch-forming mechanism, said controller including a plurality of parts adjustable into different relative positions, a member jointly controlled by said parts in accordance with their relative positions to cause operation of said stop mechanism, and means for automatically changing the relative adjustment of said parts at predetermined times to prevent operation of said stop mechanism by said member.

10. In a sewing machine having stitch-forming mechanism including a stitching shaft and a stop mechanism for stopping said machine after the formation of a predetermined number of stitches, mechanism for controlling said stop mechanism comprising a rotary controller, means for rotating said controller at a predetermined speed relative to that of said stitching shaft, said controller including a plurality of coaxial parts angularly adjustable into different relative positions, a member jointly controlled by said parts in accordance with their relative positions to cause operation of said stop mechanism at certain points in the rotation of said controller, and means for preventing operation of said stop mechanism at each of said points on alternate rotations of said controller.

11. In a machine for sewing on buttons having a plurality of pairs of holes, button holding means, stitch-forming mechanism, means for relatively moving said holding means and stitch-forming mechanism to cause the latter to form stitches through a pair of holes, means for relatively shifting said holding means and stitch-forming mechanism to cause the latter to form stitches through different pairs of holes, and means for operating said moving means and shifting means, said operating means including connections adjustable to cause said moving means and shifting means to operate at different relative speeds, whereby to vary the number of stitches formed through the several pairs of holes.

12. In a machine for sewing on buttons having a plurality of pairs of holes, button holding

means, stitch-forming mechanism, means including a cam for relatively moving said holding means and stitch-forming mechanism to cause the latter to form stitches through a pair of holes, means including a cam for relatively shifting said holding means and stitch-forming mechanism to cause the latter to form stitches through different pairs of holes, and means for driving said cams at variable relative speeds whereby to vary the number of stitches formed through the several pairs of holes.

13. In a machine for sewing on buttons having a plurality of pairs of holes, button holding means, stitch-forming mechanism, means for relatively moving said holding means and stitch-forming mechanism to cause the latter to form stitches through a pair of holes, means for relatively shifting said holding means and stitch-forming mechanism to cause the latter to form stitches through different pairs of holes, means for operating said moving means and shifting means, said operating means including connections adjustable to cause said moving means and shifting means to operate at different relative speeds, whereby to vary the number of stitches formed through the several pairs of holes, stop mechanism for said machine, and means operated in definite time relation with said shifting means for controlling said stop mechanism.

14. In a machine for sewing on buttons having a plurality of pairs of holes, button holding means, stitch-forming mechanism, means for relatively moving said holding means and stitch-forming mechanism to cause the latter to form stitches through a pair of holes, means for relatively shifting said holding means and stitch-forming mechanism to cause the latter to form stitches through different pairs of holes, means for operating said moving means and shifting means, said operating means including connections adjustable to cause said moving means and shifting means to operate at different relative speeds, whereby to vary the number of stitches formed through the several pairs of holes, stop mechanism for said machine, and means operated in synchronism with said moving means for controlling said stop mechanism.

15. In a machine for sewing on buttons having a plurality of pairs of holes, button holding means, stitch-forming mechanism, means for relatively moving said holding means and stitch-forming mechanism to cause the latter to form stitches through a pair of holes, means for relatively shifting said holding means and stitch-forming mechanism to cause the latter to form stitches through different pairs of holes, means for operating said moving means and shifting means at variable relative speeds whereby to vary the number of stitches formed through the several pairs of holes, stop mechanism for said machine, and means operated in definite time relation with said shifting means for controlling said stop mechanism, said controlling means being adjustable to cause operation of said stop mechanism after the formation of a variable number of stitches.

16. In a machine for sewing on buttons, stitching mechanism, work clamping mechanism, means including a cam for relatively moving the stitching mechanism and work clamping mechanism to sew a group of stitches in two holes of a button, said cam having a plurality of alternatively operative cam grooves including portions shaped respectively to cause a tying stitch to be formed after a different number of stitches

have been sewn in the group, the tying-stitch-forming portions of the several grooves being differently positioned angularly of the cam, whereby said tying stitches are formed at different angular positions of the cam.

17. In a machine for sewing on buttons having a plurality of pairs of holes, stitching mechanism, work holding mechanism, means including a cam for relatively moving said holding mechanism and stitching mechanism to cause the latter to form stitches through a pair of holes, means for operating said cam at a constant time speed ratio with respect to the stitching mechanism, said cam having a plurality of alternatively operative cam grooves having portions positioned and shaped respectively to relatively position the stitch forming mechanism and the work so that tying stitches are formed in different positions of said cam means including a second cam for relatively shifting the stitching mechanism and the work holding mechanism so that groups of stitches are sewn through two pairs of holes in a four hole button, and means for operating said second cam at variable speeds with respect to the speed of said first mentioned cam, whereby to cause the relative motion imparted by said second cam to occur just after the first mentioned cam causes a tying stitch to be made.

18. In a machine for sewing on buttons, stitch-forming mechanism, work holding means, means including a cam, rotated in constant time relation with respect to the stitch-forming mechanism, for relatively moving the stitch-forming mechanism and work holding means to form a group of stitches through two holes of a button, said cam having a plurality of alternatively operative cam grooves including portions differently positioned angularly of the cam and shaped respectively to cause a tying stitch to be formed after a different number of stitches have been formed in the group, and a stop mechanism having controlling means adjustable while the machine is at rest to cause the latter to stop after each tying stitch has been formed or after each alternate tying stitch has been formed.

19. In a machine for sewing on buttons, stitching mechanism, work clamping mechanism, means including a cam for relatively moving the stitching mechanism and work clamping mechanism to sew a group of stitches in two holes of a button, said cam having a plurality of alternatively operative cam grooves including portions differently positioned angularly of the cam and shaped respectively to cause a tying stitch to be sewn after a different number of stitches have been sewn in the group, said tying stitches occurring at different angular positions of the cam, and means operated in adjustable timed relation with said cam for stopping the machine after the formation of any tying stitch.

20. In a machine for sewing on buttons having several pairs of holes, stitch-forming mechanism, work holding means, a device adjustable to relatively reciprocate said holding means and mechanism at uniformly recurring intervals for a variable time period so as to cause said mechanism to form a variable number of stitches through the several pairs of holes, means operated in timed relation with said device and being adjustable to stop the machine after the formation of said stitches, and means operated in variable time relation with said device for relatively shifting said holding means and mechanism to

divide said stitches in substantially equal numbers over the several pairs of holes.

21. In a machine for sewing on buttons, stitch-forming mechanism, work holding means, a device adjustable to relatively reciprocate said holding means and mechanism at uniformly recurring intervals through an operating cycle of variable duration so as to cause said mechanism to form a variable number of stitches through a pair of holes of a button, means operated in timed relation with said device and adjustable to stop the machine after one or several of said operating cycles of the device, other means operated in variable time relation with said device for relatively shifting said holding means and mechanism after an operating cycle of said device for causing said mechanism to form the next group of stitches through another pair of holes of the button, and means for rendering said other means inoperative for sewing on buttons having only one pair of holes.

22. In a machine for sewing on buttons, button holding means, stitch-forming mechanism, means including a controlling member operating in constant time relation with said stitch-forming mechanism for relatively moving said holding means and stitch-forming mechanism to cause the latter to form automatically groups of button-attaching stitches each completed by a tying stitch, said moving means having provision for varying the number of stitches formed in each of such groups while causing each group to be completed by a tying stitch irrespective of the number of stitches therein, and means for automatically stopping the machine adjustable to operate at the completion of one or more of any of said stitch groups.

23. In a machine for sewing on buttons, button holding means, stitch-forming mechanism, means including a controlling member operating in constant time relation with said stitch-forming mechanism for relatively moving said holding means and stitch-forming mechanism to cause the latter to form automatically groups of button-attaching stitches each completed by a tying stitch, said moving means having provision for varying the number of stitches formed in each of such groups while causing each group to be completed by a tying stitch irrespective of the number of stitches therein, and means, also operating in constant time relation with said stitch-forming mechanism, for automatically stopping the machine adjustable to operate at the completion of one or more of any of said stitch groups.

24. In a machine for sewing on buttons, button holding means, stitch-forming mechanism, means for relatively moving said holding means and stitch-forming mechanism to form stitches suitably positioned to attach a button, said moving means including a cam and means for moving the same in constant time relation with the operation of said stitch-forming mechanism, said cam having alternatively operative portions adapted respectively to cause the automatic formation of groups of stitches of a different number each and each completed by a tying stitch irrespective of the number of stitches therein, and means for automatically stopping the machine adjustable to operate at the completion of any of said stitch groups.

25. In a machine for sewing on buttons, having a plurality of pairs of holes, button holding means, stitch-forming mechanism, means operating in constant time relation with said stitch-forming mechanism for relatively moving said

holding means and stitch-forming mechanism in one direction to cause the latter to form groups of stitches through said pairs of holes, said moving means having provision for varying the number of stitches formed in each group while causing each group to be automatically completed by a tying stitch irrespective of the number of stitches therein, means for automatically stopping the machine adjustable to operate at the completion of any two of said stitch groups, and means for relatively shifting said holding means and stitch-forming mechanism in another direction after the completion of one of said groups to cause the two groups of stitches to be formed through different pairs of holes.

26. In a machine for sewing on buttons having a plurality of pairs of holes, button holding means, stitch-forming mechanism, means for relatively moving said holding means and stitch-forming mechanism in one direction to cause the latter to form groups of stitches through said pairs of holes, said moving means having provision for varying the number of stitches formed in each of such groups while causing each group to be automatically completed by a tying stitch irrespective of the number of stitches therein, means for automatically stopping the machine adjustable to operate at the completion of any two of said stitch groups, and means for relatively shifting said holding means and stitch-forming mechanism in another direction after the completion of one of said groups to cause the two groups of stitches to be formed through different pairs of holes, said shifting means being adjustable in accordance with the numbers of stitches in said groups.

27. In a machine for sewing on buttons having a plurality of pairs of holes, button holding means, stitch-forming mechanism, means operating in constant time relation with said stitch-forming mechanism for relatively moving said holding means and stitch-forming mechanism in one direction to cause the latter to form groups of stitches through said pairs of holes, said moving means having provision for varying the number of stitches formed in each of such groups while causing each group to be automatically completed by a tying stitch irrespective of the number of stitches therein, means for automatically stopping the machine adjustable to operate at the completion of any two of said stitch groups, and means for relatively shifting said holding means and stitch-forming mechanism in another direction after the completion of one of said groups to cause the two groups of stitches to be formed through different pairs of holes, said shifting means being adjustable in accordance with the numbers of stitches in said groups.

28. In a machine for sewing on buttons having a plurality of pairs of holes, button holding means, stitch-forming mechanism, means operating in constant time relation with said stitch-forming mechanism for relatively moving said holding means and stitch-forming mechanism in one direction to cause the latter to form groups of stitches through said pairs of holes, said moving means having provision for varying the number of stitches formed in each of such groups while causing each group to be automatically completed by a tying stitch irrespective of the number of stitches therein, means also operating in constant time relation with said stitch-forming mechanism for automatically stopping the machine adjustable to operate at the completion of any two of said stitch groups, and means for relatively shifting said holding means and stitch-forming mechanism in another direction after the completion of one of said groups to cause the two groups of stitches to be formed through different pairs of holes, said shifting means being adjustable in accordance with the numbers of stitches in said groups.

pletion of any two of said stitch groups, and means for relatively shifting said holding means and stitch-forming mechanism in another direction after the completion of one of said groups to cause the two groups of stitches to be formed through different pairs of holes, said shifting means operating in variable time relation with said moving means and stopping means.

29. In a machine for sewing on buttons having a plurality of pairs of holes, button holding means, stitch-forming mechanism, means operating in constant time relation with said stitch-forming mechanism for relatively moving said holding means and stitch-forming mechanism in one direction to cause the latter to form groups of stitches through said pairs of holes, said moving means including a cam having alternatively operative portions adapted respectively to cause the automatic formation of stitch groups of a different number of stitches each and each completed by a tying stitch irrespective of the number of stitches therein, means for automatically stopping the machine adjustable to operate at the completion of any two of said stitch groups, means including a second cam for relatively shifting said holding means and stitch-forming mechanism in another direction after the completion of one of said groups to cause the two groups of stitches to be formed through different pairs of holes, and means for driving said second cam at a variable speed relative to said first named cam.

30. In a sewing machine having stitch-forming mechanism including a stitching shaft and a stop mechanism for stopping the machine after the formation of a predetermined number of stitches, mechanism for controlling said stop mechanism comprising a rotary controller, means for rotating said controller at a predetermined speed relative to that of the stitching shaft, a member operable under the control of said controller to cause operation of said stop mechanism at each of a plurality of points in each rotation of said controller, and means for preventing said member from causing operation of said stop mechanism at each of said points on alternate rotations of said controller.

31. In a sewing machine having stitch-forming mechanism including a stitching shaft and a stop mechanism for stopping the machine after the formation of a predetermined number of stitches, mechanism for controlling said stop mechanism comprising a rotary controller, means for rotating said controller at a predetermined speed relative to that of the stitching shaft, a member operable under the control of said controller to cause operation of said stop mechanism at each of a plurality of points in each rotation of said controller, and means associated with and carried by said controller for preventing said member from causing operation of said stop mechanism at each of said points on alternate rotations of said controller.

32. In a sewing machine having stitch-forming

mechanism including a stitching shaft and a stop mechanism for stopping the machine after the formation of a predetermined number of stitches, mechanism for controlling said stop mechanism comprising a rotary controller, means for rotating said controller at a predetermined speed relative to that of the stitching-shaft, a member operable under the control of said controller to cause operation of said stop mechanism at each of a plurality of points in each rotation of said controller, and means for preventing said member from causing operation of said stop mechanism at alternate points on one rotation of the controller and at the remaining points on the succeeding rotation thereof.

33. In a sewing machine having stitch-forming mechanism and stop mechanism for stopping the machine after the formation of groups of stitches, mechanism for controlling said stop mechanism comprising a rotary controller having means for causing operation of said stop mechanism at certain points in the rotation of said controller, means for rotating said controller in timed relation with respect to said stitch-forming mechanism, said controller having an element rotatable therewith but oscillatable with respect thereto into positions adapted respectively to render the controller operative and inoperative to cause operation of said stop mechanism at said points, and means for oscillating said element in timed relation with respect to the rotation of said controller.

34. In a machine for sewing stitches in groups of a variable number each, stitch-forming mechanism, stop mechanism for stopping the machine, means, including a cam, for controlling the kind of stitches formed, means for rotating said cam in timed relation with respect to said stitch-forming mechanism, said cam having a plurality of alternatively operative cam grooves including portions differently positioned angularly of the cam and shaped respectively to cause a tying stitch to be formed after a different number of stitches have been formed in the group, and means carried by the cam for causing operation of said stop mechanism and adjustable to cause such operation after the formation of one or more tying stitches.

35. In a machine for sewing stitches in groups of a variable number each and in different positions respectively, stitch-forming mechanism, work-holding means, means, including a cam, for controlling the kind of stitches formed, means for driving said cam in timed relation with respect to the stitch-forming mechanism, said cam having a plurality of alternatively operative cam grooves shaped respectively to cause a tying stitch to be formed after a different number of stitches have been formed in a group, means, including a second cam, for relatively shifting said stitch-forming mechanism and work holding means, and means for driving said second cam from said first-named cam at a selective variable speed.

FRANKLIN A. REECE.
